UNITED STATES PATENT OFFICE.

WILLIAM F. EYLES, OF GRAND RAPIDS, MICHIGAN.

ELECTRICALLY-WOUND CLOCK.

Application filed January 21, 1924. Serial No. 687,411.

This invention relates to an automatic electrically wound clock adapted for use particularly with automobiles but capable of use anywhere any clock is desired. The invention is concerned with many novel mechanisms and arrangements of parts for effectively winding the spring actuating the clock mechanism periodically, in practice every five minutes; for causing said winding through the action of applied electric power; for making sure and durable contacts which will not get out of order either under the vibration of an automobile on which it may be carried, or from arcing of the current used; for preventing the running down of the clock and total using up of the entire power of the spring should, at any time, the source of electric energy used be cut off or otherwise be incapacitated; and for generally simplifying and making practical a clock of this character. All of these features, as well as many others not specifically stated at this time, together with novel constructions for attaining the same, will appear as understanding of the invention is had from the following description, taken in connection with the accompanying drawings, in which,

Fig. 1 is an elevation of the mechanism with one of the side plates removed to show the same, various parts being left out for sake of clearness of disclosure.

Fig. 2 is a vertical section through the clock on the line 2—2 of Fig. 3 illustrating the means used to wind the spring.

Fig. 3 is a central vertical section through the clock mechanism.

Fig. 4 is a view similar to that shown in Fig. 1 with additional parts removed to disclose other features of construction covered up or obscured in the showing in Fig. 1.

Figs. 5 and 6 are perspective views of details of construction, more specific outline of which will appear in the description of the mechanism, and

Fig. 7 is a diagrammatic outline of the electrical circuit used in winding the clock spring.

Like reference characters refer to like parts in the different figures of the drawings.

In the construction, a series of circular plates 1, 2 and 3 are used, the same being spaced apart by spacing sleeves 4 and connected together in such spaced apart relation in any conventional manner. Plate 3 is at the front, plate 1 at the back and plate 2 between said plates 1 and 3, and as connected

together form a supporting frame for the clock mechanism. The intermediate plate 2 at its upper portion is cut away where the electro magnets are mounted so as not to interfere with the same. Said plates and sleeves 4 are preferably made of brass.

A relatively heavy bar 5 is permanently secured across the frame and between the plates 1 and 3 serving as a support for two cores 6 of two electro magnets, the windings of which are indicated at 7. The cores are supported at one end and are attached to the bar 5 by means of screws 8, extending horizontally and in parallel relation to each other. Adjacent the free ends of the cores, an armature plate 9 is located and is pivotally mounted between the plates 1 and 3, having pintles 10 projecting from each end and near the upper edge thereof, which pintles pass through suitable openings in said plates 1 and 3. Two arms 11 (Fig. 6) extend downwardly in spaced apart relation from the plate 9 at one end thereof, and a third arm 12 extends downwardly from adjacent the opposite end thereof. This plate 9 is of iron so as to be attracted by the cores when the same are energized and rendered magnetic.

A pawl 13 is pivotally mounted at one end on a pivot pin 14 extending between the arms 11. A spring 15 is coiled around a rod 16 located between arms 11 and has an arm 15^a extended to bear against the upper side of the pawl 13, normally impelling the same downwardly so as to always keep it in engagement with a ratchet wheel 17 (Figs. 2 and 3) formed on a sleeve 18 which is rotatably mounted on a stud shaft 19 attached to and projecting forwardly from the back plate 1. A coiled spring 20 is located around the sleeve 18 in front of the ratchet wheel 17 and at one end is attached to said wheel. A second pawl 21 engages with the ratchet wheel 17 (see Fig. 2) to prevent any backward movement thereof under the influence of the spring which normally is wound to a certain degree of tension.

The free end of the spring is formed into a loop 22 (see Fig. 3) which passes through a slot in the end of a shaft 23 rotatably mounted on and passing through the plates 2 and 3. On the front end of this shaft, the minute hand of the clock is adapted to be attached. On the shaft back of the front plate 3 a gear 24 is fixed and back of the gear a second ratchet wheel having twelve teeth is

secured, as indicated at 25. The gear 24 meshes with a pinion 26 secured to a second gear 27 and fixed on a second shaft 28. Gear 27 engages with a second pinion 29 on a third shaft 30 at the front end of which the seconds hand is adapted to be secured. A third gear 31 is fixed on shaft 30 and a short bar 32 is also fixed to this shaft. Gear 31 meshes with a pinion 32^a (see Fig. 1) which is operatively connected with the usual escapement mechanism used in clocks or watches. When the spring 20 is under tension, it serves to drive the train of gearing outlined the same as in any clock, governed and controlled by the usual escapement mechanism which is not shown herein as it is old and well known and forms no part of the invention in the present case.

On the front side of the plate 2, a bracket 33 is permanently secured and spaced apart therefrom are two like brackets 34 which are fixed to the plate. A rod 35 is disposed between the upper end of the bracket 33 and the upper bracket 34, and a like rod 36 between the lower end of the bracket 33 and the lower bracket 34. These rods 35 and 36 are parallel and serve as guides on which an irregularly shaped member 37 is slidably mounted. The member 37 has an upwardly projecting part 38 through which the upper rod 35 freely passes, and at one end has a horizontal arm 39, the free end of which is turned upward, as at 40 so as to come directly in line with the part 12 on the armature plate 9, lying in the same vertical plane therewith. Member 37 is also provided with a downwardly extending portion 41 slotted at its lower end, through which the lower rod 36 passes, as shown in Fig. 5. On the rod 36 and embracing the lower end of the portion 41 is a U-shaped member 42 formed with upwardly extending legs 43 and 44, the latter of which terminates in a cam projection 45 while the former has an extension of reduced thickness, as indicated at 46 in which a slot 47 is cut. The legs 43 and 44 of the U-shaped member pass at opposite edges of the portion 41 and with the movement of either member on the rod 36, the other must move with it, as is evident.

A coiled spring 48 is located around the upper rod 35 between the bracket 34 and the projecting portion 38 of member 37 and a second spring 49 is located around the rod 36, both being subject to compression and normally acting to move the member 37 so that its portion 38 is brought against the upper portion of bracket 33 and the part 40 against the arm 12, as shown in Fig. 4. The lower spring 49 is also a torsion spring, one end thereof being extended to bear against the face of the plate 2 (see Fig. 4), the opposite end being bent to pass through slot 47 and then extended to provide an arm 50 which terminates in an end section 51 bent at right angles to the arm 50 and so located that in one

position of the member 42, as shown in Fig. 3, it interposes in the path of movement of the member 32 fixed on shaft 30.

A block of insulating material, 53 is mounted between the member 37 and the plate 2, passing through a slot 52 in the member 37 which is longer than the said block. This block is formed with outwardly extending flanges 54 between member 37 and plate 2 and has a projecting portion 53^a passing through a slot 55 in plate 2 (see Fig. 7), said slot being of the same length as slot 52. At one end of the block a metal piece 56 is secured. A flat bar of spring metal, indicated at 57 bears at its free end against the piece 56 and is secured at its opposite end to a post 58 mounted on the plate 2 but insulated therefrom by insulation disks 59. A wire 60 connects the post 58 with one end of the windings 7 of the electro magnets. A second contact bar 61 similar to the bar 57 bears at its free end against the block and at its opposite end is permanently secured to a post 62 connected to the plates 2 and 1 and insulated therefrom by disks 63. At the outer end of post 62 a binding post 64 is provided to which a wire 65 is secured, which wire connects to the opposite end of the series winding for the electro magnets, an electric battery 66 being interposed in the length of wire 65, as shown in Fig. 7. It is evident that if block 53 is moved to the left (referring to Fig. 7) until the piece 56 comes under the contact bar 61, an electric circuit is completed through the electro magnet windings which will serve to energize the cores 6 with a consequent movement of the armature plate 9 toward the cores and a longitudinal movement of the pawl 13 whereby the ratchet wheel 17 is rotated and spring 20 partly wound and its tension increased.

Projecting from the lower part of the bracket 33 is an arm 67 in which a tapered pin 68 is adjustably mounted. This pin extends over the cam projection 45, as shown in Fig. 4 in one position of the member 37 and acts to turn the U-shaped member 42 against the torsion of spring 36. As shown in Fig. 1, the cam projection 45 extends under the second ratchet wheel 25 and serves as a dog to engage therewith, being disengaged gradually therefrom as the tapered pin acts on the said part 45 to force the same downward, as will appear in the following description of the operation of the mechanism:

In the beginning, the spring 20 is wound to a certain predetermined degree of tension under which the mechanism will best run and which remains nearly constant at all times during the operation of the clock. Assuming the parts to be in the position shown in Fig. 4, both contacts 57 and 61 are in contact engagement with the bridge piece 56 and the circuit is completed through the magnet windings. The cores 6 draw

the armature plate 9 toward their free ends whereby the spring 30 is given a small additional winding. At the same time the arm 12 by its engagement with the part 40 moves the member 37 to the right (referring to Fig. 4), carrying the part 45 away from the tapered pin 68 and under the ratchet wheel 25 whereupon, at the end of the travel of the member 37, said part 45 engages with a tooth of the wheel 25 and holds the member 37 against return movement. It is obvious that the springs 48 and 49 are compressed in this operation. It is also evident that at the beginning of the movement of the member 37, the block 53 remains at rest or until the member 37 has moved over far enough so that the end of the slot 52 comes against the left hand end of said block whereupon it is moved so that the bridge piece 56 moves away from contact with the contact bar 61, breaking the circuit. The mechanism then runs under the combined action of the springs 20, 48 and 49, the force of the springs 48 and 49 being transmitted through the part 45 to the ratchet wheel 25. In the operation of the mechanism, the wheel 25 turns in the direction of the arrow, indicated in Fig. 1 and member 37 is gradually moved to the left as the movement of said wheel permits, being forced by the springs 48 and 49. This movement of the member 37 does not affect the block 53 due to the fact that slot 52 is longer than the block and the circuit remains broken. As the said member 37 moves to the left, the part 45 rides under the tapered pin 68 and at a predetermined point is disengaged from the wheel freeing the member 37 for complete movement to the left with a consequent movement of the block 53 carrying the bridge piece 56 over to position to again complete the circuit, whereupon the operation is again carried out as described.

The wheel 25 having twelve teeth, and the shaft making a turn once in an hour, the rewinding of the spring occurs every five minutes. The movement of the block 53 in making and breaking the circuit is very rapid, obviating arcing. The final movement of the member 37 to the left after disengagement of the part 45 from wheel 25 carries said part 45 farther under the tapered pin 68, turning the U-shaped member 42 so as to bring the extension 51 into the path of movement of the member 32. If, for any reason, the electric current should be off and the magnets not energized as would ordinarily occur, the mechanism cannot run down with a total loss of tension in spring 20, as within thirty seconds the member 32 comes against the part 51 and is stopped thereby bringing the entire mechanism to a stop. As soon as the current is again available, the magnets operate to carry the member 37 over to the left, automati-

cally freeing the member 32 and the clock is again ready to run, spring 20 having the requisite tension.

From the foregoing it is apparent that I have produced a clock which is continually kept in wound condition and which will operate so long as a suitable source of electric energy is maintained to furnish the power for winding. The construction is very durable and is capable of withstanding any and all vibrations to which it might be subjected in service when used with an automobile. The electrical contacts do not get out of order. Severe practical road tests of the clock on an automobile covering a long period of time have proved the reliability of the mechanism under hardest service. The construction is relatively simple and inexpensive to produce. The appended claims define the invention and it is to be considered that all forms of structure coming within the scope of said claims are comprehended by the invention.

I claim:

1. In a clock, a driving spring, electrical means for winding the same, a movable member actuated on said winding of the spring, spring means acting on the movable member and resisting its actuation, means connecting the first spring with the clock mechanism, and means connecting the movable member with the clock mechanism whereby said mechanism is driven by the driving spring and by said spring means acting against the movable member, substantially as described.

2. In a clock, clock mechanism, a driving spring connected therewith, electrical means for winding the spring, a movable member, spring means acting on said movable member to move it in one direction, separable means connecting the movable member with the clock mechanism to aid in driving the same, and means for moving the movable member against the force of said spring means simultaneously with the winding of the driving spring, substantially as described.

3. In a clock, clock mechanism, a driving spring connected therewith, electro magnets, a movably mounted armature at one end of the magnets, means for winding the driving spring on movement of the armature toward the magnets, a movable member, switch mechanism operated by the movement of the movable member, means for moving the said member in one direction by the movement of the armature toward the magnets, spring means for moving said member in the opposite direction, means connecting the movable member with the clock mechanism, and an electric circuit in which the windings of the magnets are included and with which the switch mechanism is associated whereby the circuit is completed on movement of said member in one direction to a predetermined

position and broken on movement of the member by said armature to a second position, substantially as described.

4. In a clock, clock mechanism, a driving spring connected with said clock mechanism, a ratchet wheel connected with the spring, electro-magnets, a movably mounted armature located at one end of the magnets, a pawl on the armature having one end engaging the ratchet wheel, a second ratchet wheel on said shaft, a member movably mounted adjacent the shaft and to one side of the second ratchet wheel, spring means acting on said member to move it in one direction, means on the armature engaging against said member to move it in the opposite direction on movement of the armature toward the magnets, a second member connected with the first member to move therewith and also pivotally mounted and having a portion adapted to engage with the second ratchet wheel, means for automatically disconnecting said portion from the ratchet wheel on movement of the first member under the influence of said spring means a predetermined distance, an electric circuit including the magnet windings, and switch means actuated by said movable member to close the circuit after disconnection of said portion from the second ratchet wheel and break the circuit on movement of the said member a distance in the opposite direction under the action of the armature.

5. In a device of the character described, combination of elements defined in claim 4, combined with means for automatically stopping the clock mechanism after a short interval on failure of the source of electric supply for the circuit, substantially as described.

6. In a clock, clock mechanism, a spring for driving the same, a movable member having a slot therein, a block of insulating material mounted to project through said slot, electro magnets, a movably mounted armature plate at one end of the magnets, means actuated by the movement of the plate toward the magnets for winding the spring, means for moving the member on movement of the armature plate toward the plates, means normally tending to move the member in the opposite direction, wires leading from the magnet windings, one of said wires having a source of electric energy interposed in its length, and a contact member connected with the free end of each wire and bearing at its free end against the said block, said block having a metal bridge piece at one end against which one of the contact members bears at all times, the adjacent ends of the contact members being separated a short distance.

7. In a clock, clock mechanism, a spring for driving the same, a pivotally mounted armature, means for magnetically actuating

the armature in one direction at periodic intervals, means connected to the spring operated by said armature when it is actuated to tension said spring, and additional spring means coupled with means for tensioning the same when the armature is actuated operatively associated with the clock mechanism to aid in driving the same, substantially as described.

8. In a clock, clock mechanism including a shaft having a ratchet wheel thereon, a movably mounted armature, magnetic means for swinging the armature in one direction, a pawl carried by the armature engaging with the ratchet wheel to turn the same in one direction, a spring wound by the rotation of said shaft, additional spring means operatively associated with the clock mechanism to aid the first spring in driving the same when tensioned, means for tensioning said additional spring means at the same time the first spring is wound, and means for periodically magnetically operating said armature to wind the first spring and tension the second named spring means, substantially as described.

9. In a clock, clock mechanism, a torsion spring for driving the same, a pivotally mounted armature, magnetic means for periodically moving the armature in one direction, means for winding the torsion spring from said armature on its movement in said direction, additional spring means operatively associated with the clock mechanism to aid in driving the same when tensioned, and means for tensioning said additional spring means simultaneously with the winding of the torsion spring.

10. In a clock, clock mechanism, a torsion spring for driving the same, a pivotally mounted armature, magnetic means for periodically moving said armature in one direction, means interposed between the armature and torsion spring for winding the same on said movement of the armature, additional spring means operatively associated with the clock mechanism to aid in driving the same, and means for simultaneously tensioning said additional spring means with the winding of the first spring.

11. In a clock, clock mechanism and a rotating member, a spring to drive said clock mechanism, electric means to periodically tension said spring including a reciprocable circuit breaker and an arm movable with said reciprocable circuit breaker into the path of said rotating member when the circuit breaker is in circuit closing position and out of the path of the rotating member when the circuit breaker is in open circuit position.

In testimony whereof I affix my signature.

WILLIAM F. EYLES.
